(57) **CLAIM**

The ornamental design for a video magnifier, as shown and described.

DESCRIPTION

FIG. 1 is a front perspective view of the video magnifier.

FIG. 2 is a front view of the video magnifier.

FIG. 3 is a rear view of the video magnifier.

FIG. 4 is a right side view of the video magnifier.

FIG. 5 is a left side view of the video magnifier.

FIG. 6 is a top plan view of the video magnifier; and,

FIG. 7 is a bottom plan view of the video magnifier.

The broken lines inside a secure member in FIGS. 3, 4, and 5 that are immediately adjacent to the claimed areas represent the bounds of the claimed design while all other broken lines including the monitor are directed to environment and are for illustrative purposes only; the broken lines form no part of the claimed design.
